(57) **CLAIM**

The ornamental design for a housing for a positive airway pressure apparatus, as shown and described.

DESCRIPTION

FIG. 1 is a top front right perspective view of a housing for a positive airway pressure apparatus in accordance with the claimed design;

FIG. 2 is a front elevation view of the design of FIG. 1;

FIG. 3 is a rear elevation view of the design of FIG. 1;

FIG. 4 is a right side elevation view of the design of FIG. 1;

FIG. 5 is a left side elevation view of the design of FIG. 1;

FIG. 6 is a top plan view of the design of FIG. 1;

FIG. 7 is a bottom plan view of the design of FIG. 1;

FIG. 8 is a bottom front right perspective view of the design of FIG. 1; and,

FIG. 9 is a bottom rear left perspective view of the design of FIG. 1.

The dot-dash broken lines in the figures represent a boundary between claimed and unclaimed subject matter and form no part of the claimed design.

The dash-dash broken lines in the figures represent unclaimed subject matter and form no part of the claimed design.

1 Claim, 9 Drawing Sheets
